UNITED STATES PATENT OFFICE.

ERNEST KIRK, OF NIAGARA, NORTH DAKOTA.

SHOCK AND BUNDLE LOADER.

1,150,206.

Specification of Letters Patent. Patented Aug. 17, 1915.

Application filed July 16, 1914. Serial No. 851,358.

To all whom it may concern:

Be it known that I, ERNEST KIRK, a citizen of the United States, residing at Niagara, in the county of Grand Forks and State of North Dakota, have invented certain new and useful Improvements in Shock and Bundle Loaders; and I do declare the following to be a full, clear, and exact description of the invention, such as will enable others skilled in the art to which it appertains to make and use the same.

This invention relates to new and useful improvements in shock and bundle loading machines and the primary object of the invention is to provide a machine of this character whereby shocks or bundles will be engaged, lifted and conveyed or elevated into a wagon without breaking or loosening the same.

A further object of the invention resides in providing an improved forward or front carrier on the device for engaging and lifting the bundles and still another object resides in providing such a carrier as may be capable of disposition to various positions at the will of the operator.

A still further object resides in providing an improved carrier which is provided with an improved means for support on the main frame of the device and also with an improved means for the operation thereof to various positions as desired.

A still further object resides in providing a device which is simple and durable in construction, inexpensive to manufacture, and one which will be very efficient and useful in operation.

With these and other objects in view, my invention consists in the novel features of construction, combination and arrangement of parts as will be hereinafter referred to, and more particularly pointed out in the specification and claims.

In the accompanying drawings forming a part of this application, Figure 1 is a plan view of the device constructed in accordance with my invention, parts being broken away and parts disclosed in section: Fig. 2 is a side elevation thereof with parts in section, the conveyer being disclosed in its operative position: Fig. 3 is a similar view showing the conveyer in its inoperative position: Fig. 4 is a vertical section taken on line 4—4 of Fig. 1: Fig. 5 is a vertical transverse section through the conveyer taken on line 5—5 of Fig. 11. Fig. 6 is an enlarged plan view

of the main conveyer, parts of the operating means therefor being disclosed in section: Fig. 7 is a vertical section as seen on line 7—7 of Fig. 6: looking in the direction of the arrows: Fig. 8 is an enlarged fragmentary section through the conveyer as seen on line 8—8 of Fig. 7, looking in the direction of the arrows: Fig. 9 is a vertical transverse section as seen on line 9—9 of Fig. 6: Fig. 10 is a similar view as seen on line 10—10 of Fig. 7: Fig. 11 is a vertical transverse section as seen on line 11—11 of Fig. 1 and, Fig. 12 is an enlarged fragmentary plan view of the frame of the device, with parts broken away and parts in section, disclosing clearly certain operating mechanisms of the device.

In describing the invention I shall refer to the drawings in which similar reference characters designate corresponding parts throughout the several views and in which 1 indicates a main supporting frame having the supporting wheels 2 and 3 mounted at the sides thereof and mounted in the forward portion of said frame 1 is an endless conveyer 4 which is adapted to engage and lift bundles and the like from the surface of the ground and convey the same to a transversely extending and endless conveyer 5 which is mounted at the rear portion of the frame. This transversely extending conveyer 5 has an upwardly inclined portion 6 whereby the contents thereof may be conveyed to a wagon or other receptacle (not shown.) My invention, however, involves particularly the structure of the front or forward carrier 4, including the means for supporting and operating the same and the following detailed description will be devoted particularly to this portion of the device.

The main frame 1 consists of certain longitudinal and transverse bars, as clearly disclosed in the drawings, and mounted between a pair of longitudinal bars of said frame adjacent the forward ends thereof are the upright posts 7. These posts may be said to be fulcrumed to the bars of the frame intermediate their ends whereby to permit of certain movement of the same in the frame and such movement is limited in view of the flexible connections 8 which are secured to said frame and to the lower ends of said posts 7. While these flexible connections limit the swinging movement of the posts in one direction, a transverse bar of

the frame limits the movement of said posts in the opposite direction.

Pivots carried between the posts 7 is an enlarged crank shaft 9, the crank portion of which extends loosely through the side bars 10 of the conveyer 4. It might be here stated also that the ends of this crank shaft 9 which are pivotally mounted in the posts 7 are capable of adjustment in the latter to 10 adjust the position of the carrier proper with respect thereto, as may be found desirable. As stated above, the crank shaft 9 has the ends thereof mounted adjacent the upper ends of the posts 7 and mounted between 15 the lower ends of said posts 7 is an additional crank shaft 11. This latter crank shaft, has the crank portion thereof of greater depth than the crank portion of the shaft 9. The crank portion of this 20 shaft 11 is furthermore also loosely disposed through the side bars of said conveyer 4, the engagement of said crank shaft with the conveyer being at points adjacent the lower ends thereof. It will thus be seen 25 that while this conveyer is properly supported in the main frame, the same is capable of movement therein in a manner which will be hereinafter more particularly set forth.

30 Adjustably connected with the upper ends of each of the posts 7 is one end of a coil spring 12, the lower or opposite ends of said coil springs being engaged with the outer faces of the side bars 10 of said conveyer 35 4. The normal tendency of these coil springs is to draw upwardly upon the conveyer frame to seat the latter upon the main frame 1 but when said conveyer frame is disposed in its operative position, that is, 40 an upwardly inclined position with respect to the main frame, the weight of said conveyer will just overbalance the tension of said springs so that said conveyer frame may be properly positioned under tension of 45 said springs. The tension of said springs, however, may be adjusted by the adjusting means shown in connection with the operation of said springs and the posts 7.

50 Mounted for oscillation on certain longitudinal bars of the frame 1 at one side of the latter is a crank shaft 13. One end of this crank shaft is provided with a crank arm 14 which has connection with one end of a link 15, the opposite end of said link 55 being pivotally connected with one side bar of the conveyer 4 at a point adjacent the upper end of the latter. The crank portion of the shaft 13 operates between a pair of longitudinal bars of the frame 1 and has a 60 foot pedal or the like 16 connected therewith whereby upon the actuation of said foot pedal said crank shaft will be actuated to raise or lower the conveyer frame as desired. When the conveyer frame is raised, 65 said frame is adapted to rest upon the main

frame 1 and in the raising thereof the frame will be aided considerably by the springs 12 above referred to. When lowered, the weight of the conveyer and frame proper will retain the frame in its operative position. The movement of this frame in its lowered position is limited by means of stop keepers 17 carried on the main frame which receive in contact therewith portions of the crank shaft 11 therein. Any desired means 70 may be provided for the operation of the crank shaft 13 whereby to retain said conveyer 75 4 securely in its operative position.

The above described operating means for the conveyer frame proper which, as mentioned is the object of the invention, forms an important and essential part of the invention but my invention also resides in the particular structure of the conveyer proper which will be described presently. The side 80 bars 10 of the conveyer frame 4 are connected at different points by transverse bars 18 and mounted for rotation between the upper ends of the side bars 10 of said conveyer 4 and beyond the uppermost transverse bar 18 85 is a shaft 19. One end of this shaft extends considerably beyond one side bar 10 thereby to have connection with an operating means to be hereinafter more particularly set forth and keyed or otherwise secured on said shaft 95 between the side bars 10 of the conveyer frame are the three sprockets 20, which are spaced at equal distance from one another in the frame. Trained over these sprockets 20 are the endless chains 21 and said chains 100 are also trained over additional and idle sprockets 22 which are hingedly mounted in brackets or bearings carried on the lowermost bar 18 of the conveyer frame. These three endless chains extending over the 105 sprockets as above described form the foundation of my improved endless conveyer proper. Certain of the links of the chains 21 are provided with bearing boxes 23 and mounted for oscillation therein are the ends 110 of transversely extending crank shafts 24. These crank shafts are arranged in staggered relation to one another, it being of course understood that through the provision of a trio of endless chains and transverse bars connecting the same, an endless conveyer of two sections is thus formed. As 115 stated, these transversely extending crank shafts which are mounted for oscillation in the bearing boxes are arranged in staggered 120 relation to one another and the same are provided with arcuate teeth 25 to engage the bundles on the surface of the ground as the device is propelled and the conveyer 125 operated.

In view of the fact that the engaging means on the conveyer consists of crank shafts mounted for oscillation in bearings thereon it will be appreciated that in the operation of said carrier, under ordinary 130

conditions, these crank shafts will be oscillated in their bearings as the same reach the uppermost portion of the conveyer and thrown to opposite positions as the same 6 assume a position on the lower reach of the conveyer thus returning in an opposite position, which is undesirable. I have provided a means therefore, to avoid this inconvenience and to this end each crank shaft 10 24 is provided at its outer end with a removable crank arm 26 which carries at its free end a roller 27.

Mounted on the inner face of each side bar of the conveyer frame 4 is a strip 28 15 forming a track or the like which extends to points adjacent the ends of said conveyer frame. The upper extremities of the strips 28 are bent somewhat inwardly and downwardly as indicated at 28' and clearly 20 disclosed in Fig. 7 of the drawings. This track or the like 28 with its upper bent extremity 28' receives thereon the rollers 27 carried on the ends of the crank arms and thus each crank arm which forms a means for carrying 25 a bundle, is properly supported in position in the operation of the conveyer. Also secured to each side bar of the frame 4 at the upper extremity of the conveyer is a guard shield or the like 29 which is articulated in design one portion of which is somewhat 30 irregularly constructed, as clearly shown in Fig. 7 of the drawings. This guard shield 29 cooperates with the bent portion 28' to form a race-way 29' which receives 35 therein the rollers of the crank shaft as the latter tend to pass over the upper sprocket 20. As these crank shafts pass around the upper sprocket 20 and assume a position on the lower reach of the conveyer 40 the rollers 27 will be guided by the lower portions of the guard shields 29, as clearly disclosed in Fig. 7, and thus said crank shaft will be prevented from swinging to an undesirable position. The same will 45 retain a position to enable the bundles carried thereby to be readily dumped onto the transversely extending conveyer but said crank shaft will be overturned in the proper position as the same leaves the raceway and 50 thus the same will be in a position to again engage the bundles when said crank shafts are moved toward the forward end of the device. No such raceways or the like are provided at the forward or lower portion 55 of the conveyer frame 4 but shields of articulate design and indicated in the drawings as 30 are so provided to limit the outward swinging movement of said crank shafts as the same pass around the lowermost 60 sprocket 22.

As above stated, the lowermost or idle sprockets 22 are carried on the lowermost transverse bar 18 within the conveyer frame and it must be here stated that said bar is 65 capable of certain adjustment within the

frame 4. Through this medium the slack in the endless chains 21 may be taken up when desired. This adjustment may, of course, be through the medium of any approved and well known means. 70

This carrier is provided at its forward and lower end with a means for preventing injury to the operating parts thereof in the event of stones and other rigid obstructions being strewed in the path of the device. To 75 this end, I provide yielding members in the spaces between the endless chains 21 over which members the transversely extending crank shafts 24 operate and when the prongs or teeth of said crank shafts engage 80 stones and other similar obstructions, thereby tending to detain the device, a yielding action will occur which is particularly caused by the space of said shafts 24. These yielding members each consist of a U-shaped 85 bar 31, the arms of which are slidably disposed through openings in certain of the lowermost of transverse bars 18 of the conveyer frame 4. The base portion of the U-bar has a channel shaped or arcuate shield 90 32 connected therewith the base portion of which faces forwardly and over which the crank shaft 24 operates. Encircling the arms of the U-bar between the base portion 95 thereof and the lowermost transverse bar 18 are the coil springs 33, the normal tendency of which is to force the U-bar outwardly and downwardly. Thus it will be seen that when the operating portions of the conveyer 100 meet obstructions in the path of the device, portions of the conveyer may yield on the tension of the springs and ride over the obstruction, particularly in view of the oscillatory movement of the crank shaft on the conveyer proper. 105

As stated previously, the bundles, grain and the like, are engaged by the teeth on the crank shaft of the forward conveyer as the device is so called and carried upwardly 110 on said conveyer to a point where the same are dumped onto a transversely extending conveyer 5, the latter being so disposed as to convey the same to a wagon or other receptacle (not shown). This latter conveyer 115 5 is of the usual construction, with one exception that being the formation of certain transverse slats thereon. These slats in the drawing are indicated as 34, the same being secured a short distance from their ends to 120 endless chains similar to the chains referred to in the front or forward conveyer. The ends of said slats, however, have rollers 35 mounted thereon and the inclined frame of the conveyer and a portion of the main frame are provided on both sides thereof 125 with tracks 36 over which the rollers 35 operate.

As before stated, the wheels 2 and 3 are supporting wheels for the main frame 1 but 130 the wheel 2 is also designed for use as a driv-

ing wheel. In carrying out this idea, the axle of the wheel 2 is provided with an enlarged sprocket 37 over which extends an endless chain 38. This chain 38 extends 5 rearwardly of the wheel 2 and is trained over the sprocket 39 which is mounted on a shaft 40 the latter being supported on the main frame 1 rearward of the wheel 3. Also mounted on this shaft 40 is a bevel gear 41 10 and mounted for rotation in bearings 42 in the main frame 1 is a longitudinally extending shaft 43. Mounted on the rear end of the shaft 43 is a bevel pinion 44 meshing with the bevel gear 41 and a similar pinion 15 45 mounted on the forward end of said shaft 43 to mesh with a bevel gear 46 which is carried on a rotatable shaft 47 the latter being rotatable in bearings on the frame 1 just below the forward carrier 4. Pivottally 20 carried on the shaft 47 is a pair of links 48 the outer ends of which have rotatably mounted therein a shaft 49 on which is carried a sprocket 50. This sprocket 50 has a chain 51 extending thereover which also extends 25 over an additional sprocket 52 carried on the shaft 47.

Pivottally carried on the shaft 49 are the lower ends of an additional pair of links 53 the upper ends of which are loosely carried 30 on the extending portion of the upper rotatable shaft 19 carried on the front carrier frame 4. Also carried on this projecting portion of the shaft 49 is a sprocket 54 over which extends a chain 55 the latter being 35 trained over an additional sprocket 56 carried on the shaft 49. Through the medium of this construction it is perfectly obvious that as the device is propelled so as to rotate the driving and supporting wheels 3, the 40 front carrier may be operated and in any position of said front carrier, the operating mechanism will be effective.

Mounted on the rear end of the shaft 43 is a sprocket 57 over which is trained a 45 chain 58 the latter being connected with a sprocket 59 on one of the shafts forming an operating end of the carrier 5. In this matter it will be seen that the rear or transverse carrier 5 may be also operated by the same 50 driving mechanism as operates the front carrier. A clutch mechanism 60 is, however, provided in connection with the sprocket 57 whereby the front carrier may be operated without operating the rear carrier and an 55 additional clutch mechanism 61 is arranged in connection with the shaft 43 and the pinion 45 whereby the operation of the front carrier may be discontinued while the rear carrier is in operation.

60 Connected with the forward end of the frame 1 at one side of the conveyer 4 is a front supporting trunk 62 which has a tongue 63 and draft attaching devices 64 connected therewith. Through the medium 65 of this mechanism, draft animals may be at-

tached thereto and the device propelled over the field.

From the foregoing description of the construction of my improved device the operation thereof will be readily understood 70 and it will be seen that I have provided a simple, inexpensive and efficient means for carrying out the objects of the invention.

While I have particularly described the elements best adapted to perform the functions set forth, it is obvious that various changes in form, proportion and in the minor details of construction may be resorted to within the scope of the appended 75 claims, without departing from the spirit 80 or sacrificing any of the principles of the invention.

Having thus described my invention, what I claim is:

1. In a shock or bundle loader of the 85 class described, a frame supported on wheels, a pair of crank shafts mounted for oscillation on said frame, a conveyer supported on said crank shafts to move therewith, means for raising and lowering said 90 conveyer to its inoperative and operative positions respectively, and spring means in connection with the frame and conveyer to aid in disposing the conveyer to its inoperative position.

2. In a shock or bundle loader of the class described, a frame supported on wheels; a pair of crank shafts mounted for oscillation on said frame, a conveyer frame supported on said crank shafts to move therewith, means for raising and lowering said 100 conveyer frame to its inoperative and operative positions respectively, and coil springs engaged at one of their ends with the main frame and at their opposite ends 105 with the conveyer frame to aid in raising said conveyer frame to its inoperative position.

3. In a machine of the class described, a frame supported on wheels, a pair of crank 110 shafts mounted for oscillation thereon, the depressions of said crank shafts being of unequal depth, a conveyer operatively mounted on said crank shafts to move therewith, the weight of the conveyer tending to 115 normally lower the same to its inoperative position, means to limit the downward movement of the conveyer with respect to the frame, means in connection with one of said crank shafts for raising said conveyer to its inoperative position, said conveyer in the last mentioned position being adapted to rest on its frame, and spring 120 means in connection with the frame and conveyer to aid in raising the latter to its 125 inoperative position.

4. In a device of the class described the combination with a movable member; of a conveyer mounted thereon including a frame, upper and lower sprockets supported 130

therein, endless chains trained over the alining sprockets, transversely extending shafts mounted on said chains, engaging members carried on the shafts and yielding means 5 provided at the lower portion of said frame and adapted to be engaged by the shafts when the engaging members on the latter meet obstructions in the path of travel.

5. In a device of the class described the 10 combination with a movable member, of a conveyer supported therein including a frame, upper and lower sprockets operatively mounted therein, endless chains trained over the alining upper and lower 15 sprockets, a plurality of transversely extending shafts mounted on said chains engaging members carried on said crank shafts, and spring forced shields supported in the lower portion of said frame and 20 adapted to be engaged by said shafts when the engaging members thereon meet obstructions in the path of travel.

6. A machine of the class described comprising a truck, a pair of spaced posts fulcrumed between their ends thereon, a pair 25

of cranks carried by each post and located on opposite sides of the fulcrum thereof, a receiving conveyer interposed between the two pairs of cranks and pivoted thereto, and means for raising and lowering said conveyer to its inoperative and operative positions respectively. 30

7. A machine of the class described comprising a truck, a movable member mounted thereon, a pair of cranks carried by said 35 movable member, a receiving conveyer supported by said cranks, means to raise and lower said conveyer respectively to its inoperative and operative positions, and spring means in conjunction with the movable 40 member for assisting in returning the conveyer to its inoperative position.

In testimony whereof I have hereunto set my hand in presence of two subscribing witnesses.

ERNEST KIRK.
